UNITED STATES PATENT OFFICE

115,139

DESIGN FOR A DECORATED FEATHER

Otis F. Wood, New York, N. Y.

Application October 14, 1938, Serial No. 80,455

Term of patent 14 years

To all whom it may concern:

Be it known that I, Otis F. Wood, a citizen of the United States and resident of New York city, in the county of New York and State of New York, have invented a new, original, and ornamental Design for a Decorated Feather, of which the following is a specification, reference being had to the accompanying drawing, forming part thereof, and in which

Fig. 1 is a front plan view of a decorated feather showing my new design,

Fig. 2 is a rear plan view of said decorated feather,

Fig. 3 is an enlarged fragmentary view showing the stem upon an enlarged scale as compared to Figs. 1 and 2, and

Figs. 4 and 5 are transverse sectional views upon the lines 4—4 and 5—5 of Fig. 3.

The leading distinctive feature of the design resides in the decorated stem of the feather.

I claim:

The ornamental design for a decorated feather, substantially as shown and described.

OTIS F. WOOD.
